UNITED STATES PATENT OFFICE

EUGENE L. SCHELLENS, OF RIDGEWOOD, NEW JERSEY, ASSIGNOR TO C-S ENGINEERING COMPANY, OF ENGLEWOOD, NEW JERSEY, A CORPORATION OF DELAWARE

FEED WATER HEATING APPARATUS

Application filed December 17, 1929. Serial No. 414,635.

This invention relates to feed water heating devices and is particularly useful for locomotive boilers, and in the present disclosure I have illustrated my invention as applied 5 to this field of usefulness. Furthermore, the invention is particularly useful for that type of feed water heater which delivers the water to the boiler through a spray valve which is adapted to spray the water into an ascending 10 column of steam as it passes upwardly from the boiler and then out to a point of use on the locomotive. This type of heater is very fully disclosed in my Patent No. 1,802,125, April 21, 1931.

15 The principal objects of the invention are to improve feed water heaters or temperature equalizers, as they are sometimes called, of the general type disclosed in the above mentioned application in such a way as to 20 combine with the spray valve a means for making it perform the function of a stop valve in case it is necessary to grind the boiler check valve and to prevent an excess quantity of moisture from reaching the auxiliaries 25 on the locomotive with the steam taken from the heater.

How the foregoing objects, as well as any other objects which may appear hereinafter, or are incident to my invention, are obtained 30 is illustrated in a preferred form in the accompanying drawings, wherein—

Fig. 1 is a vertical section through my improved heating apparatus, and

Fig. 2 is a partial side elevation of a locomotive illustrating the application of my improvements thereto.

By referring to the drawings it will be seen that the boiler 3 is provided with an opening 4 at the top around which I place 40 a flanged collar 5. Adjacent the opening 4 and secured to the collar 5 I place an open ended casing 6 which has a substantially cylindrical central portion 7 on the interior extending downwardly into the opening 4.

45 Feed water either from the injector or from the customary feed water heater on the locomotive is introduced to the central chamber 7 through the feed water inlet 8. In an aperture in its lower portion the central chamber 50 7 is provided with a valve seat member 9

which is threaded into position as clearly shown in Fig. 1. A spray valve 10 adapted to seat upwardly against the seat member 9 controls the flow of the water coming through the inlet 8. The valve 9 has an upwardly extending frame structure 11 which enters into the interior of the chamber 7 and which is provided with the annular shoulders 12 and 13.

The upper open end of the casing 6 is closed 60 by means of the cover plate or bonnet 14 suitably held in place in any desired manner, as by the bolts 15, there being a gasket 16 between the casing 6 and the bonnet 14.

65 Into a central opening in the bonnet 14 is threaded the bushing member 17, the member 17, in effect, forming a part of the cover or bonnet 14.

70 Passing downwardly through the cover and the bushing member 17 is a spindle or shaft 18 which has threaded engagement at 19 with the opening 19'. Between the upper portion of the shaft 18 and the bushing 17 is a suitable packing 20 held in place by means of the packing gland 21 and the nut 75 22.

75 Removably mounted on the upper end of the spindle or shaft 18 is a handle or operating wheel 23 by means of which the shaft can be rotated, and it will be seen that this handle is provided with lugs 24 which are adapted to take against the upper surface of the bonnet 14.

80 At its lower end the spindle 18 carries a shoulder portion 25 which is arranged in opposition to the shoulders 13 and 12 on the valve body. Between the shoulders 12 and 15 I place a compression spring 26. This makes the valve 10 a spring loaded valve 85 which will yield sufficiently to permit the water to enter as it comes in under pressure 90 through the inlet 8.

95 It will be seen that by screwing the spindle outwardly by means of the handle 23, the shoulder 25 can be brought against the shoulder 13. The abutment means thus provided serves to hold the valve 10 tightly against its seat, and in this way the spray valve can be made to function as a stop valve so that the boiler check valve can be ground when neces- 100

sary, the boiler inspection rules specifying the necessity for such a stop valve. Furthermore, in the operative or normal position the lugs 24 on the handle 23 serve as an indicating means for showing when the spindle 18 is screwed in sufficiently far to permit the spray valve 10 to function as it should. In other words, all that it is necessary to do is to turn the handle 23 until the lugs 24 contact with the top of the bonnet or cover plate 14.

Set in the opening 4 is an inwardly tapering ring or collar 26' which cooperates with the casing 6 to form a chamber in which the water and the steam can be mixed and which also serves as a supporting structure by virtue of its cross member 27 at the bottom, for retaining the valve and its spindle in position should the bonnet be removed for cleaning or other purpose. The ring or collar 26' is in open and free communication with the interior of the boiler and the steam from the boiler passes upwardly therethrough and thence into the casing 6 where it is thoroughly mixed with the incoming water by means of the several baffles 28.

In order to ensure a positive circulation of steam, as well as to prevent the formation of air pockets which would otherwise accumulate in the structure as a result of the liberation of oxygen when the colder water is brought up to boiling temperature, I provide the steam offtake 29 under the control of the valve 30 which is connected by means of the pipe 31 to the auxiliary header 32 located on top of the boiler just forward of the cab 33.

A circulation of steam which is just sufficient to clear the device of air pockets is secured by virtue of the fact that the auxiliary header is in turn connected to the dome 34 by means of the auxiliary header dry pipe 35, so that when steam is drawn from the auxiliary header to run any of the auxiliaries on the locomotive, a flow of steam will be induced through the pipe 31. The quantity of the steam will not be very large, for the primary supply for the auxiliaries will come from the pipe 35 which is connected to the dome 34, but sufficient circulation will be ensured to prevent the formation of air pockets, as well as to ensure that the heating device or temperature equalizer 6 performs its function in the proper way.

The arrangement just described, it will be seen, prevents the drawing of a large quantity of steam from the heater to the auxiliaries, as has sometimes been done in previous practice where all of the steam for the auxiliaries was taken from the heater. Such steam is ordinarily extremely wet and causes considerable trouble in the auxiliaries, but by my improved arrangement the amount of steam drawn from the heater will be such a small proportion of the total amount used by the auxiliaries that the quantity of water or mois-

ture taken over from the heater 6 will be immaterial.

I claim:

1. In a heater of the character described, the combination of a casing adapted to be secured to a locomotive boiler, a water inlet to said casing, a spray valve associated with said inlet for controlling the flow of the incoming water, a spindle extending to the outside of and threaded into said casing, opposing shoulders on valve and spindle, a spring interposed between said shoulders yieldingly holding the valve in closed position and means for turning the spindle to compress said spring and bring said shoulders into contact to lock the valve in closed position. 75

2. In a heater of the character described, the combination of a casing adapted to be secured to a locomotive boiler, a water inlet to said casing, a spray valve associated with said inlet for controlling the flow of the incoming water, a spindle extending to the outside of and threaded into said casing, opposing shoulders on valve and spindle, means for turning the spindle to bring said shoulders into contact to lock the valve in closed position, and indicator means on the spindle adapted to register with the outside wall of the casing when the parts are in normal or operative position. 85

3. In a heater of the character described, the combination of an open ended casing adapted to be secured to a locomotive boiler, a water inlet to said casing, a removable cover or bonnet for the upper open end, a spray valve associated with said inlet for controlling the flow of the incoming water, means extending through said bonnet for locking said valve in closed position, and means for supporting said valve and said locking means when said bonnet is removed. 95

4. In a heater of the character described, the combination of an open ended casing adapted to be secured to a locomotive boiler, a water inlet to said casing, a removable cover or bonnet for the upper open end, a spray valve associated with said inlet for controlling the flow of the incoming water, means extending through said bonnet for locking said valve in closed position, means for supporting said valve and said locking means when said bonnet is removed, and means on the locking means adapted to register with the outside of the bonnet to indicate when the parts are in normal or operative position. 110

5. In a heater of the character described, the combination of a casing having a water inlet, a spray valve associated with said inlet, a spindle threaded into the casing, opposed shoulders on the spindle and on the valve, a spring interposed between said shoulders, and abutment means for limiting the movement of the valve with respect to the spindle, said abutment means being adapted to lock 125

the valve in closed position upon rotation of said spindle.

6. In a locomotive, the combination of a boiler, a heater of the character described having communication with the boiler and provided with a steam outlet, a dome in communication with the boiler, an auxiliary header, a connection between the header and the dome and a connection between said steam outlet and said header.

7. In a heater of the character described, the combination of an open ended casing adapted to be secured to a locomotive boiler, a water inlet to said casing, a cover or bonnet for the upper open end, a valve associated with said inlet for controlling the flow of the incoming water, a spindle extending through said bonnet, a spring reacting between the spindle and the valve for yieldingly holding the valve in closed position, opposing shoulders on spindle and valve normally acting as stop means to prevent excessive opening of the valve, and means outside the bonnet for moving said spindle to compress the spring and bring the shoulders into contact to lock the valve in closed position.

In testimony whereof I have hereunto signed my name.

EUGENE L. SCHELLENS.
